US0D1050079S

(12) **United States Design Patent** (10) **Patent No.:** **US D1,050,079 S**
(45) **Date of Patent:** **** Nov. 5, 2024**

(54) **WIRELESS CONTROLLER**

(71) Applicant: **TIMOTION TECHNOLOGY CO., LTD.**, New Taipei (TW)

(72) Inventor: **Yu-Chen Wu**, New Taipei (TW)

(73) Assignee: **TIMOTION TECHNOLOGY CO., LTD.**, New Taipei (TW)

(**) Term: **15 Years**

(21) Appl. No.: **29/897,349**

(22) Filed: **Jul. 13, 2023**

(51) LOC (14) Cl. **14-03**

(52) U.S. Cl.

USPC **D14/218**

(58) **Field of Classification Search**

(57) **CLAIM**

The ornamental design for a wireless controller as shown and described.

DESCRIPTION

FIG. 1 is a perspective view of a wireless controller showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is the second perspective view showing the wireless controller.

The broken lines shown in the figures are for the purpose of illustrating portions of the wireless controller and form no part of the claimed design.

1 Claim, 8 Drawing Sheets
